CLAIM

I claim the ornamental design for a three point chest harness,
as shown and described.

DESCRIPTION

FIG. 1 is a front elevation view of the three point chest harness showing my new design;

FIG. 2 is a back elevation view thereof;

FIG. 3 is a left side elevation view thereof;

FIG. 4. is a right side view of the chest strap; and,

FIG. 5 is a fragmented rear view.

The broken lines in FIGS. 1, 2, and 5 represent stitching.
